TORPEDO

John Hays Hammond, Jr., Gloucester, Mass.

Application January 5, 1934, Serial No. 705,358

10 Claims. (Cl. 114—21)

This invention relates to the control of self-propelled bodies and more particularly to a method and means for controlling the path of a torpedo and for detonating the war head of the torpedo under predetermined conditions.

More specifically, the invention provides for changing the path of a torpedo as it passes beneath a ship so as to cause the torpedo to strike the bottom of the ship, preferably at or near the center of the hull. Means is also provided to detonate the war head of the torpedo when it is closely adjacent the hull, in a position where the maximum damage may be effected.

This is accomplished by mechanism controlled by the influence of the hull when the torpedo passes in proximity thereto, which mechanism sets the vertical rudder of the torpedo to bring the torpedo up into engagement with the bottom of the hull. The mechanism may also control suitable timed means for detonating the explosive charge at a predetermined time after the actuation of the vertical rudder, preferably at the time the torpedo strikes the hull.

In one embodiment of the invention, the change in hydrostatic pressure on the top of the torpedo, due to the influence of the adjacent hull is utilized for the above purpose.

It has been found that, when a body travels thru the water, it causes the formation of a pressure wave, which produces definite pressures on different portions of the surface of the object, depending on the shape of the object and the speed at which it is travelling. While the body is travelling in deep water and at a uniform speed, this pressure distribution is constant. If, however, the body, comes into proximity with another body, this pressure distribution is materially changed, causing the pressures on certain areas of the body to change rapidly. This may be because of a pressure wave reflected from the second body or because of the reaction caused by the influence of the second body.

The present invention provides a mechanism whereby this change in pressure on a portion of the torpedo first causes the torpedo to be directed sharply upward and then, after a predetermined interval of time, causes the explosion of the warhead.

The invention also provides a means whereby the detonation of the war-head of the torpedo is delayed a predetermined time after the torpedo has passed under the hull of the ship in order to allow the explosion to occur near the central portion of the vessel, where it would be most effective.

The invention also consists in certain new and original features of construction and combinations of parts hereinafter set forth and claimed.

Although the novel features which are believed to be characteristic of this invention will be particularly pointed out in the claims appended hereto, the invention itself, as to its objects and advantages, the mode of its operation and the manner of its organization may be better understood by referring to the following description taken in connection with the accompanying drawings forming a part thereof, in which

Fig. 1 is a vertical longitudinal section of the forward portion of a torpedo provided with one embodiment of the present invention;

Fig. 2 is a partial section taken on line 2—2 of Fig. 1;

Fig. 3 represents diagrammatically the after-body of the same torpedo;

Fig. 4 is a view similar to Fig. 1 of a modified form of the invention;

Fig. 5 is a view similar to Fig. 1 of another modified form of the invention;

Fig. 6 diagrammatically illustrates the course of a torpedo attacking an enemy vessel.

Like reference characters denote like parts in the several figures of the drawings.

In the following description and in the claims, parts will be identified by specific names for convenience, but they are intended to be as generic in their application to similar parts as the art will permit.

Referring to the accompanying drawings, and more particularly to Figs. 1 to 3, there is shown a waterborne body such as a torpedo having a water tight hull or skin 9, and arranged to be propelled in the usual manner by propellers 10 located at the after end. The hull 9 is provided with a transverse bulkhead 11, forming two compartments 13 and 14, the former being filled with an explosive charge 15, such for example as TNT.

A hole is provided in the hull 9 at the top of the compartment 14. This hole is covered by a diaphragm of flexible material 16 to which is attached a rod 17 which loosely passes through a hole in an arm 18, which is pivoted to a frame 19 secured to the bulkhead 11. The arm 18 is provided with a socket 20 into which fits the upper end of a rod 21, provided with a threaded portion which screws through the bracket 19. The rod 21 passes through a water tight bearing in a cupped shaped member 22 which is secured to the lower surface of the hull 9 at which point the hull is provided with a hole to allow access to the end of the rod 21. The lower end of the rod

21 is square-shaped as at 23 to receive a key or wrench for rotating the rod 21. A spring 25 surrounds the rod 17 between the arm 18 and the diaphragm 16. Pivots connected to the lower end of the rod 17 is an arm 26 which is pivoted for rotation to the bracket 19. The arm 26 is provided with lugs 27 and 28 at the respective ends, the former engaging a pin 29 which is carried by a plunger 30. This plunger 10 is slidably mounted in the bulkhead 11 and is provided with a collar 31, secured thereto. Between this collar and the bulkhead 11 is a compression spring 33. The end of the plunger 30 is formed into a firing pin 35 which is adapted 15 to explode a detonator 36 mounted in a frame 37 which is carried by the bulkhead 11.

Slidably mounted in the frame 19 is a rod 40 to one end of which is pivotally attached an H-shaped finger 41 which is provided with a projection 42 which at suitable times cooperates with a projection 43 of the bracket 19. A collar 45 is secured to the rod 40. Between this collar and the finger 41 is a tension spring 46 which normally holds the finger 41 in engagement with 20 a projection 47 provided on the plunger 30. Secured to the other end of the rod 40 is a piston 48 which reciprocates in a cylinder 49. This cylinder is provided with a port 50, the flow of air through which is controlled by a needle valve 30 51.

The plunger 30 is provided with a lug 55 which cooperates with an arm 56 having an extension 57. The arm 56 is pivoted to a clock-work mechanism 58 and is provided with a projection 59 which rides on a cam 60 driven by the clock-work mechanism 58. This cam is provided with a notch 61 for receiving the projection 59 at suitable times. A spring 61 is secured to the clock-work mechanism 58 and engages the extension 51, tending to 40 turn it and the arm 56 in a clock-wise direction. The cam 60 is secured to a shaft 62 which is driven at a predetermined rate of speed by the clock-work mechanism 58. To the shaft 62 is secured an arm 63 which normally engages a pin 64. A 45 pin 65 is provided which at suitable times is engaged by the arm 63 for limiting the motion of the cam 60.

For automatically starting the clock-work mechanism 58 a heavy weight 165 is secured to 50 the end of a flat spring 66, the upper end of which is fastened to the casing of the clock-work mechanism 58. The weight 165 is provided with a projection 67 normally engaging a finger 68 which controls the starting of the clock-work 55 mechanism. Engaging the end of the finger 68 is a spring 69 which is supported on a bracket 70.

The lug 28 of the arm 26 cooperates with a pin 74 carried by a valve spindle 75 which reciprocates in a valve casing 76. The valve spindle 75 60 is provided with two collars 75 and 76. Between the collar 75 and the valve casing 76 is a compression spring 77. The valve spindle 75 is provided with a lug 77 which normally engages the extension 51. The interior of the valve casing 76 communicates with a supply of fluid under pressure (not shown) by means of a pipe 78. Also communicating with the interior of the valve casing 76 is a pipe 79 which communicates with the interior of a cylinder 80 located in the after body 70 (Fig. 3). Slidably mounted in the cylinder 80 is a piston 81 which is operatively connected to an arm 82, pivotally mounted on the hull 9 of the torpedo at 83.

The torpedo is provided with the usual vertical 75 and horizontal rudders 85 and 86 respectively.

The latter are operated by means of a link 87 from the horizontal steering engine 88 which is supplied with fluid under pressure from a pipe 89 and is controlled by a valve 90 operated in a well known manner from the depth control mechanism 91. The horizontal steering engine 88 and the depth control mechanism 91 are of any standard construction which is well known in the art. Secured to the link 87 is a collar 92 which is located in the path of travel of the arm 82. 10

In the operation of the invention shown in Figs. 1 to 3, before the torpedo is fired, the rod 21 is turned, by means of a key or wrench, which fits over the head 23, an amount dependent upon the depth at which the torpedo is to run. This 15 puts the spring 25 under a compression corresponding to the hydrostatic head at this depth, so that when the torpedo has reached this depth, the pressure on the outside of the diaphragm 16 will be equal to the pressure of the spring 25, thus 20 causing the arm 26 to assume the position shown in Fig. 1.

When the torpedo is fired, the inertia of the weight 165 causes it to be moved backwardly relative to the torpedo, thus disengaging the projection 67 from the finger 68, which is moved upwardly under the action of the spring 69, thus causing the clock-work mechanism 58 to start turning the cam 60 at a predetermined speed. After the cam 60 has rotated a sufficient amount, 30 the projection 59 of the arm 56 will drop into the notch 61 thus allowing the arm 56 to be rotated in a clock-wise direction under the action of the spring 61. This causes this arm to disengage the lug 55 of the plunger 30 and also causes the extension 57 to disengage the lug 77 of the valve spindle 75.

The plunger 30 and the valve spindle 75 will then be held in the positions shown in Fig. 1 by means of the lugs 27 and 28 engaging the pins 40 29 and 74 respectively. The torpedo now travels in this condition at its predetermined depth until it reaches a position adjacent to the hull of the enemy ship 102 as shown at 101 of Fig. 6. When it has reached this position the reaction of the 45 pressure wave of the torpedo with the hull of the enemy ship 102 will cause a pressure change on the diaphragm 16, thus causing this diaphragm to be moved either in or out depending upon certain conditions, such as the speed and 50 depth at which the torpedo is running and the shape of the enemy's hull and the speed and direction at which the hull is traveling.

This motion will be communicated to the arm 26 causing it to be rotated in either a counter 55 clockwise or clockwise direction depending upon whether the diaphragm 16 is moved in or out. In either case the lugs 27 and 28 will move out of alignment with the pins 29 and 74 thus allowing the plunger 30 to move to the right under 60 the action of the spring 33 and the valve spindle 75 to move rapidly to the left under the action of the spring 77. This allows fluid under pressure to pass from the pipe 78 to the pipe 79 thence to the cylinder 80 (Fig. 3) which causes the piston 81 to be moved to the left. This in turn rotates the arm 82 in a counter clock-wise direction so that it engages the collar 92 thus forcing the horizontal rudders 85 into the hard-up 65 position. This causes the torpedo to follow the curved path denoted by the broken line 103 of Fig. 6 thus bringing the war-head into close proximity with the hull of the enemy vessel as shown at 104. 7

Since the plunger 30 has been released by the lug 27 it starts to move to the right but is restrained in this motion by means of the dash pot 49, the air in which is allowed to escape slowly 5 through the port 50 under the control of the needle valve 51. This slow motion continues until the projection 42 of the finger 41 engages the projection 43 of the bracket 19 at which time the finger 41 will be rotated in a counter clock-wise 10 direction, thus disengaging from the lug 47 which releases the plunger 30, thus allowing this plunger to be moved rapidly to the right under the action of the spring 33 until the firing pin 35 strikes the detonator 36, thus detonating the same and causing the explosive charge 13 to be exploded. This 15 action may be timed to take place directly below and at the center of the hull of the enemy ship, thus causing the maximum amount of damage to the enemy vessel.

In the modified form of the invention shown in Fig. 4 the mechanism similar to that shown in Figs. 1 and 2 has been given the same reference characters. The rod 17 in this embodiment, is 20 connected to one end of an arm 110 which is pivoted to the bracket 19. The other end of this arm is provided with a conducting segment 111 which is insulated therefrom and which selectively engages contacts 112 and 113 which are connected through the winding of a solenoid 114 and a battery 115 to a brush 116 which engages a commutator 118. This commutator is mounted on a shaft 119 of a clock-work mechanism 120. Secured to the shaft 119 is an arm 121 which normally engages a pin 122. A second pin 123 is provided for limiting the movement of the arm 121. For automatically starting the clock-work mechanism a heavy weight 125 is secured to the end of a flat spring 126, the upper end of which is fastened to 25 the casing of the clock-work mechanism 120. The weight 125 is provided with a projection 127 which normally engages a finger 128, controlling the starting of the clock-work mechanism. Engaging the end of the finger 128 is a spring 129 30 which is supported on a bracket 130.

Engaging the commutator 117 is a second brush 131 which is connected through a solenoid 132 to the conducting segment 111.

The core of the solenoid 114 normally engages 35 a collar 135 mounted on a rod 136 to one end of which is attached a piston 137 which is slidably mounted in a cylinder 138. Between the collar 135 and the cylinder 138 is a compression spring 133. This cylinder is provided with a port 139, 40 the flow of air through which is controlled by a needle valve 140. To the other end of the rod 136 is secured a block of insulating material 141 which carries a contact 142. This contact is connected through a battery 143 to a detonator 144 45 located in the explosive charge 15. The other side of this detonator is connected to a contact 145 which cooperates with the contact 142.

The core of the solenoid 132 normally engages the collar 175 of the valve spindle 75. This valve 50 reciprocates in the valve casing 76 which is connected to the two pipes 78 and 79 as described in connection with Fig. 1. The pipe 79 communicates with the cylinder 80 shown in Fig. 3. The rest of the mechanism is similar to that already 55 shown and described in connection with Fig. 3.

In the operation of the modified form of the invention shown in Fig. 4 the tension on the spring 25 is adjusted as described in connection with Fig. 1, and when the torpedo is fired, the clock-work mechanism 120 is started operating,

thereby causing the commutator 117 to be slowly rotated until the arm 121 engages the pin 123 at which time the segment 118 will have engaged the brushes 116 and 131 thus completing the circuit through the solenoids 114 and 132.

When the torpedo passes beneath an enemy ship the pressure reaction on the diaphragm 16 will cause it to be moved either in or out, thus causing the segment 111 to engage either the contact 112 or the contact 113. In either case, the 10 circuit will be closed through the solenoids 114 and 132 and the battery 115 causing these solenoids to be energized. Solenoid 132 then releases the valve 75 which is rapidly moved to the left under the action of the spring 177. This 15 allows fluid under pressure to enter the pipe 79, thus causing the horizontal rudders 86 to be thrown hard-up.

When the solenoid 114 is energized, its core 20 will be disengaged from the collar 135, thus allowing the rod 136 to be moved slowly to the right under the action of the spring 133. The speed of this motion is determined by the setting of a needle valve 140. This continues until the contact 142 engages the contact 145 which closes the 25 circuit through the detonator 144, thus exploding the charge in the war-head of the torpedo. This as already described in connection with Fig. 6 is preferably timed to take place when the torpedo is at the center and directly in contact with 30 the hull of the enemy vessel.

In the form of the invention shown in Fig. 5 the rod 17 is connected to one end of an arm 150 which is pivoted to the bracket 19. The other end of this arm normally engages the ends of 35 two arms 151 and 152 which are pivoted to two brackets 153 and 154 respectively. These brackets are mounted upon the bulkhead 11. Slidably mounted in this bulkhead is a plunger 156, which is provided with a collar 157 secured thereto. 40 Between this collar and the bulkhead 11 is a compression spring 158. The end of the plunger 156 is formed into a firing pin 159 which is adapted to explode a detonator 160 mounted in a frame 161 which is carried by the bulkhead 11. Piv- 45 tally connected to the plunger 156 is a T-shaped arm 162 which cooperates with two lugs 163 and 164 provided on the arms 151 and 152 respectively. Two springs 166 and 167 are carried by these arms and engage the T-shaped arm 162 tending to 50 hold it in a central position. Operatively connected to the two arms 151 and 152 are two pistons 170 and 171 which reciprocate in two cylinders 172 and 173. These cylinders are provided with ports 174 and 175 which are normally closed 55 by spring pressed flap valves 176 and 177. The cylinders 172 and 173 are also provided with two ports 178 and 179 the openings in which are controlled by two needle valves 180 and 181. Two compression springs 182 and 183 are mounted be- 60 tween the cylinders 172 and 173 and the arms 151 and 152 respectively.

The plunger 156 is provided with a lug 185 which at suitable times is engaged by the end of an arm 186 which is pivotally mounted upon 65 the casing of a clock-work mechanism 187. This arm is provided with a projection 188 which rides on a cam 189 secured to the shaft 190 of the clock-work mechanism 187. The cam 189 is provided with a notch 184 for receiving the projec- 70 tion 188. Also secured to this shaft is an arm 191 which normally engages a pin 192 and is limited in its motion by means of a second pin 193.

For automatically starting the clock-work mechanism 187 a heavy weight 195 is secured to 75

the end of a flat spring 196, the upper end of which is fastened to the casing of the clock-work mechanism 187. The weight 195 is provided with a projection 197 which normally engages a finger 198 controlling the starting of the clock-work mechanism. Engaging the end of the finger 198 is a spring 199 which is supported on a bracket 200. The remaining elements are similar to those described in connection with Fig. 1, 0 and are given similar reference numerals.

In the operation of the modified form of the invention shown in Fig. 5 the compression spring 25 is set as described in connection with Fig. 1. When the torpedo is fired, the clock-work mechanism 187 is started in a manner similar to that already described, thus starting the rotation of the cam 189. This continues at a slow rate until the projection 188 drops into the notch 184, thus allowing the arm 186 to drop out of engagement 5 with the lug 185. This releases the plunger 156 which moves to the right a small distance until the projections of the T-shaped arm 162 engage the lugs 163 and 164.

The mechanism remains in this position during the run of the torpedo. If the pressure on the diaphragm 16 should change gradually during this run due to the torpedo not maintaining uniform depth or due to the change of hydrostatic pressure caused by a large swell on the 25 surface of the ocean, the arm 150 will be gradually rotated first in one direction, then in the other. As it does so, the arms 151 and 152 will follow this motion keeping on contact with the arm 150. As long as the motion of the arm 150 is 30 sufficiently slow this action will continue, as the air in the cylinders 172 and 173 will escape through the ports 178 and 179 rapidly enough to allow the arms 151 and 152 to keep in engagement with the arm 150. It is thus seen, therefore, that as long as there are only gradual 35 changes of pressure on the diaphragm 16, the firing mechanism will be held in an inoperative position.

When the torpedo passes beneath a ship, however, the change of pressure on the diaphragm 16 will be rapid, thus causing the arm 150 to move rapidly in one direction to the other, as for example, in a counter clock-wise direction. As this occurs, it will force the arm 151 upward 40 rapidly, as the air in the cylinder 162 is exhausted freely by means of the flap valve 176. The arm 152, however, will not be able to follow this rapid motion due to the dash pot action of the cylinder 173 as the air can only enter this cylinder through 45 the restricted port 179. It is thus seen that in this way the arms 151 and 152 will tend to be separated. If the change of pressure on the diaphragm 16 is sufficiently strong and rapid, it 50 will cause these arms to be separated an amount great enough to allow the T-shaped arm 162 to slip between the lugs 163 and 164, thus allowing the plunger 156 to be moved rapidly to the right under the action of the spring 158 until the firing pin 159 strikes the detonator 160 which 55 will cause the explosion of the charge 15 in the head of the torpedo.

A delayed action mechanism similar to that shown in connection with Figs. 1 and 2 may be connected to the plunger 156 if desired and a valve 76 for controlling the horizontal rudders 70 may also be connected to this mechanism in a manner similar to that shown in connection with Fig. 1.

Although only a few of the various forms in 75 which this invention may be embodied have been

shown herein, it is to be understood that the invention is not limited to any specific construction, but may be embodied in various other forms without departing from the spirit of the invention or the scope of the appended claims. 5

What is claimed is:

1. In combination, a torpedo, depth control mechanism therefor, a pressure responsive device adapted to respond to hydrostatic pressure on the top, forward surface of the torpedo and means controlled by said pressure responsive device for setting said depth control mechanism into pull-up position in response to changes in pressure caused by passage of the torpedo beneath the hull of a ship whereby said torpedo is caused 15 to strike the bottom of the ship.

2. In a torpedo, a torpedo body, an explosive charge carried by said body, a detonator for exploding said charge, a horizontal rudder, a pressure-responsive device operative on the disturbance caused by the passage of the torpedo under an enemy vessel, means governed by said pressure-responsive device for operating said horizontal rudder into hard-up position and thereafter operating said detonator. 20

3. In a torpedo, a torpedo body, an explosive charge carried by said body, a detonator for exploding said charge, a horizontal rudder, a pressure-responsive device operative on the disturbance caused by the passage of the torpedo under 30 an enemy vessel, means governed by said pressure-responsive device for operating said horizontal rudder into hard-up position and thereafter operating said detonator and a timing device for locking said rudder control and said detonator control for a predetermined period after the torpedo is launched. 35

4. In a torpedo, depth control mechanism, means to actuate the same to hard-up position, a detonator, means to actuate the same, a device 40 responsive to passage of the torpedo beneath a ship adapted to initiate the operation of both of said actuating means, and means to delay the action of said second actuating means to permit the torpedo to come into proximity with the 45 center of the bottom of the ship before detonation.

5. In a torpedo, depth control mechanism, means to actuate the same to hard-up position, a detonator, means to actuate the same, a device 50 responsive to the pressure change caused by passage of the torpedo beneath a ship adapted to initiate the operation of both of said actuating means, and means to delay the action of said second actuating means to permit the torpedo 55 to come into proximity with the center of the bottom of the ship before detonation.

6. In a torpedo, steering mechanism carried thereby, means responsive to rapid changes in the external pressure to actuate said steering 60 mechanism, and means to prevent actuation of said steering mechanism by slow changes in the external pressure.

7. In a torpedo, an explosive charge carried thereby, means responsive to rapid changes in 65 the external pressure to detonate said explosive charge, and means to prevent detonation of said explosive charge by slow changes in the external pressure.

8. In combination, a torpedo, depth control 70 mechanism therefor, a pressure-responsive device in said torpedo responsive to changes in absolute hydrostatic pressure of the water surrounding the torpedo caused by passage of the torpedo beneath the hull of a ship, and means controlled by 75

5 said pressure-responsive device for setting said depth control mechanism into pull-up position in response to said changes in pressure whereby said torpedo is caused to approach the bottom of the ship.

9. In combination, a torpedo, an explosive charge carried thereby, a pressure-responsive device in said torpedo responsive to changes in absolute hydrostatic pressure of the water surrounding the torpedo caused by passage of the torpedo near a foreign object, and means controlled by said pressure-responsive device for detonating said explosive charge in response to

said changes in pressure whereby said torpedo is caused to explode while close to the foreign object.

10. In combination, a torpedo, a utility carried thereby, a pressure-responsive device in said torpedo responsive to changes in absolute hydrostatic pressure of the water surrounding the torpedo caused by passage of the torpedo near a foreign object and means controlled by said pressure-responsive device for actuating said utility in response to such changes in pressure. 5 10

JOHN HAYS HAMMOND, JR.
